(57) **CLAIM**

The ornamental design for jar, as shown and described.

DESCRIPTION

FIG. 1 is a bottom perspective view of a jar in accordance with the present invention.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof;

FIG. 7 is a bottom perspective view of a second embodiment of our new design for a jar.

FIG. 8 is a front elevation view thereof;

FIG. 9 is a rear elevation view thereof;

FIG. 10 is a left side elevation view thereof;

FIG. 11 is a right side elevation view thereof;

FIG. 12 is a bottom plan view thereof;

FIG. 13 is a bottom perspective view of a third embodiment of our new design for a jar.

FIG. 14 is a front elevation view thereof;

FIG. 15 is a rear elevation view thereof;

FIG. 16 is a left side elevation view thereof;

FIG. 17 is a right side elevation view thereof;

FIG. 18 is a bottom plan view thereof;

FIG. 19 is a bottom perspective view of a fourth embodiment of our new design for a jar.

FIG. 20 is a front elevation view thereof;

FIG. 21 is a rear elevation view thereof;

FIG. 22 is a left side elevation view thereof;

FIG. 23 is a right side elevation view thereof; and,

FIG. 24 is a bottom plan view thereof.
